UNITED STATES PATENT OFFICE.

NORMAN O. FLEMING, OF LOS ANGELES, CALIFORNIA.

BUCKET FOR DEEP-WELL PUMPS.

1,275,546.

Specification of Letters Patent. Patented Aug. 13, 1918.

Application filed July 30, 1917. Serial No. 183,625.

To all whom it may concern:

Be it known that I, NORMAN O. FLEMING, a citizen of the United States, residing at Huntington Park, Los Angeles, in the 5 county of Los Angeles and State of California, have invented a new and useful Improved Bucket for Deep-Well Pumps, of which the following is a specification.

My invention relates to the pumping art, 10 and the principal object of the invention is to provide an improved bucket for use in a deep well pump.

A further object of the invention is to provide in such a bucket a valve which is rigidly fixed to the pump rods, and which is so arranged that it moves positively with relation to the bucket.

A further object of the invention is to provide in such pump a bucket structure so 20 arranged that the bucket turns in the pump cylinder, thereby distributing the wear over the walls of the cylinder and providing for a uniform wear of the valve seat.

A further object of the invention is to provide air chambers directly at the bucket for 25 the purpose of cushioning the blow of the valve and preventing water hammer.

A further object of the invention is to provide an air chamber which is secured to 30 the pump rod but which has openings immediately adjacent to the bucket for the purpose of cushioning the blow thereon.

The further objects and advantages will 35 be made evident hereinafter or will be evident to one skilled in the pumping art from a perusal of the following specifications and inspection of the drawings.

In the drawings, which are for illustrative 40 purposes only,

Figure 1 is a section of the center of a portion of a pump embodying my invention.

Fig. 2 is a view on a plane, represented by the line 2—2 to Fig. 1, this plane being 45 viewed in the direction of the arrows.

Fig. 3 is a view on a plane represented by the line 3—3 of Fig. 1, this plane being viewed in the direction of the arrows.

My invention is adapted to be applied to 50 single or multiple bucket pumps, but has a special utility in connection with the latter. It is illustrated as applied to the upper bucket of a duplex pump, the piston rod of the lower bucket being shown at 11 and the 55 piston rod for the upper bucket being

shown concentrically therewith at 12. Secured on the bottom of the pump rod 12 is a valve 13, this valve having a spherical or conical seat 14 on which a bucket casting 15 seats. The bucket casting 15 slips inside a 60 pump cylinder 16 which is fixed in the well, and through which the water is lifted. Cup leathers 17, secured in place by threaded rings 18, serve to make a water tight joint between the bucket casting 15 and the pump 65 cylinder 16. A series of water openings 19 are provided through the piston 15, these openings being separated by ribs 20 which are curved as shown in Figs. 2 and 3 so that the water rushing upwardly therethrough 70 tends to turn the bucket bodily in the well.

The bucket casting 15 is also provided with a central hub 21 which is bored out to slide freely through a limited distance on the pump rod 12, the lower limit of its 75 movement being set by the contact of the seat 14 and the upper limit being set by the lower end of an air chamber 22. This air chamber 22 is rigidly secured to the pump rod 12 and may be extended up through 80 the well for a considerable distance. It is entirely closed except for an opening 23 at its extreme lower end, although a flexible hose 30 may be connected into its upper end, the hose 30 being in turn connected at 85 its upper end into a reservoir containing compressed air. A similar air chamber 24 is provided in the bucket 15, an opening 25 being provided in its lower end immediately adjacent to the valve 13. 90

The method of operation is as follows: Cylinders 22 and 24 being filled with air, the parts are lowered into the well and this air is compressed to a degree equivalent to the submergence. As the pump rod 12 is reciprocated, the valve 13 is moved. The pump leather 17 provides sufficient friction so that on the down stroke the valve 13 unseats from the bucket 15 allowing the water to pass between the bucket and the valve 100 and upwardly through the openings 19. This upward movement of the water, due to the inclined ribs 20, twists the bucket at each stroke. When the bucket reaches its extreme lower position and the movement 105 of the rod 12 is reversed, the bucket remains momentarily stationary, the valve 13 rising to meet it, thereby making a tight closure. Due to the fact that the bucket 15 travels upward at a variable speed, all 110

pumps accelerating from a stationary position to one of maximum movement, there is a very considerable variation in pressure during the stroke. This variation in pressure is very largely compensated for by the compression of the air in the cylinders 22 and 24. The opening 25 is so placed that it tends to collect additional air from the water which runs through between the bucket 15 and the valve 13 on each downward stroke.

If desired, the air chamber 22 may extend to a point close to the surface and compressed air may be delivered thereto through the flexible pipe 30, this air being maintained at a pressure slightly below that necessary to force air out through the openings 23. It is possible to dispense with either the cylinder 22 or 24, their action being cumulative.

I claim as my invention:—

1. In a pump, a pump rod; a valve rigidly fixed to said pump rod; a bucket having an opening therethrough and having a

small sliding movement on said rod, said bucket having a valve face adapted to contact with a valve face on said valve at the lower end of said opening for the purpose of preventing water flowing through said opening; and walls forming an air chamber integral with said bucket and with a single opening near the bottom of said bucket.

2. In a pump, a combination as in claim 1 to which is added walls forming an air chamber fixed to the pump rod with a single opening close to said bucket.

3. In a pump, a bucket; a valve for said bucket; walls forming an air chamber located above said bucket; and walls forming an air passage in open communication with said air chamber and having an opening inside said bucket near said valve.

In testimony whereof, I have hereunto set my hand at Los Angeles, California, this 17 day of July, 1917.

NORMAN O. FLEMING.
